UNITED STATES PATENT OFFICE.

JONAS NORTHRUP, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

WARP STOP MOTION FOR LOOMS.

Application filed February 8, 1927. Serial No. 166,701.

The present invention relates to an improvement in warp stop motions for looms.

Upon the breaking of the warp and the falling of a drop wire, the loom is stopped, 5 but it is sometimes a matter of difficulty to find the place where the break occurred because the upper end of the fallen drop wire is concealed in the body of the wires and the lower end is not easily visible.

10 The object of the present invention is to produce a warp stop motion which will not only stop the loom upon the dropping of a wire, but one which will open the warp at the broken point ready for piecing. To 15 this end the present invention consists in the warp stop motion hereinafter described and particularly defined in the claims.

In the accompanying drawings illustrating the preferred form of the invention, 20 Fig. 1 is an elevation of a portion of the warp stop motion embodying the invention, showing one end of the bank of drop wires; Fig. 2 is a similar view, showing the parts in different position; and Fig. 3 is a sectional elevation taken on the line 3—3, Fig. 1.

The illustrated embodiment of the invention is described as follows: The warps extend through the eyes of the drop wires 10, which are arranged in two sets 11 and 12. 30 These drop wires are supported on the drop wire bars 13 and 14, and the warps 15 pass through the holes or eyes 16 in the drop wires. While only two sets of drop wires are shown, the additional drop wire bars 17 and 18 are provided so that four sets of drop 35 wires may be used if desired. These drop wire bars are carried by heads at each end of the sets of wires. In Fig. 1 the head 20 supports these bars. The two heads are held

40 in correct position with relation to each other by the warp supporting rods 21, 22 and 23, and the frame bars 24 and 25. Below the drop wires are mounted two ladders 26 and 27, the former of which is a 45 detector slide and the latter of which is a part of the connection between the detector slide and the knock-off mechanism of the loom. These ladders consist of two side rails connected by rungs 28 and 30. The 50 lower ladder 27 normally stands fast, and the upper ladder 26 is normally reciprocated. These ladders are supported in guide-ways, one above the other, in the ladder carriers 31 and 32 on each side of the 55 loom. The heads 20 of the stop motion are

carried on the usual supporting bar 33, mounted in the usual manner in the support 34 carried by the frame 35 of the loom. Pivoted on one of the heads is the pivot shaft 36, and mounted on this pivot shaft 60 is the bell crank lever 37, of which the depending arm 38 is provided with a slot 40, which engages a pin 41 carried by the upper ladder 26. The horizontal arm of the bell crank lever 37 is connected by means of a 65 rod 42 with a vibrating member operated from some moving part of the loom, which may conveniently be the weft hammer. Continuously in the operation of the loom the rod 42 is raised and lowered by the operation of the loom, and it oscillates the bell crank lever 37 and therefore reciprocates the upper ladder 26.

So long as the drop wires are sustained in their upper position by the warp threads, 75 this reciprocation continues without any effect upon the operation of the loom. When, however, one of the drop wires is permitted to fall by the breaking of a warp thread, as, for example, the drop wire 43, 80 then it passes between the rungs of the two ladders as shown in Fig. 2, and the movement of the upper ladder to the right causes the wire 43 to engage a rung of the lower ladder 27 and thereby move the lower ladder. 85 A second bell crank lever 44, also mounted on the pivot pin 36, has a downwardly hanging arm 45, similar to the downwardly hanging arm 38 of the lever 37, which is provided with a slot 46 similar to 90 the slot 40, which slot is engaged by the pin 47 secured to the lower ladder 27. The horizontal arm of the bell crank lever 44 is provided with a projecting pin 48, which normally engages the bottom of the recess 95 49 formed in the head 50, carried by the arm 51 which is supported upon the shaft 52 and connected with the knock-off lever of the loom.

So long as all the drop wires are held in 100 an elevated position, the bell crank lever 44 is held in the position illustrated in Fig. 1, but when a drop wire falls, then the lever is turned either counter-clockwise from the position shown in Fig. 1 to the position 105 shown in Fig. 2, or clockwise in the opposite direction. The turning of the bell crank lever 44 owing to the falling of the drop wire operates to swing the arm 51 by pressure of the pin 48 against the walls of the 110

recess 49. Thus, whenever a drop wire falls it stops the loom, and coincidently therewith the traverse of the ladders causes the fallen drop wire to crowd the wires together, as shown in Fig. 2, and thereby open up the warp and indicate where the broken warp thread is located.

The bell crank lever 37 is provided with a fork 53 having two prongs 54 and 55. These prongs project over the horizontal arm of the bell crank lever 44, and the operation is such that when the loom is started up after having been stopped, as, for example, in the position shown in Fig. 2, the lower prong 54, upon the oscillation of the bell crank lever 37, will engage the lower side of the horizontal arm of the bell crank lever 44 and restore it to its original position, as shown in Fig. 1. The rod 52 upon which the swinging arm 51 is mounted, is supported in bearings 56 and 57 of a bracket 58 mounted on a second bracket 59 carried by the loom frame. The rock shaft 52 is provided with an arm 60, which in normal position, as shown in Fig. 1, rests in the open recess 61 in the ear 62. Upon the end of the arm 60 is the eye 63 of the link 64, which extends downward to and connects with the loom stopping means 65. The eye of the link 64 is held on the arm 60 by the cotter pin 66 on the one side, and the ear 62 on the other.

The head 50 supported on the lower end of the arm 51, is provided with the recess 35 49, which is engaged by the pin 48 of the bell crank lever 44, and is adjustably attached to the arm by means of the bolt 67, a nut 68 being employed to secure the bolt in place. The head is provided on its side 40 with a recess 70, which receives the arm 51, the bolt 67 securing the head in proper position on the arm. The arm is slotted at 71 to permit relative movement of the head and arm.

45 The present inventor is the same Jonas Northrop who is the patentee of the warp stop motion illustrated and described in the patent granted January 13, 1925, No. 1,522,901. In that case a stationary ladder 50 13 was employed, and a reciprocating detector bar 15. The warp was opened by the engagement of the detector bar with a fallen drop wire, which pushed the drop wires to one side, as shown in Fig. 6. In the present 55 construction two ladders are employed, and one is constantly reciprocated and the other normally stands fast. When a drop wire falls the stationary ladder is moved by the normally moving ladder, and the drop wires 60 are opened by a movement parallel to themselves, whereas in the former construction the drop wires were opened by a tipping movement. In the present construction, 65 after the wires are opened they will stand in open position, whereas in the former pat-

ent they tend to return to their original closed position by reason of the use of the spring-pressed spreader 16. In the patented construction the spreader was located at the center of the loom. Consequently, when a drop wire fell near one side of the warp, a very considerable number of wires were displaced, whereas in the present construction only a few are moved laterally in order to open the warp, and these few rapidly restore themselves to normal position after the loom is started up again.

70 One of the good features of the present construction resides in the use of devices for engaging the fallen drop wire in such manner as to move it parallel to itself in a direction to open the warp. In the illustrated embodiment these comprise the two ladders, one of which picks up the other owing to the resistance which the upper end 75 of the drop wire encounters by being pressed against the adjacent drop wires. Another feature of importance resides in the elimination of toothed bars, which have always been a source of more or less inconvenience 80 in devices of this general character. Another advantage of the construction flows from the fact that the rungs of the ladders do not greatly impede the vision so that the fallen drop wire can easily be seen by the 85 operative when the warp motion stops the loom. Other features of advantage inherent in the present construction will be obvious to persons skilled in the art.

Having thus described the invention, what 90 is claimed is:

1. A warp stop motion for looms having, in combination, a set of drop wires, means for supporting the drop wires, a detector ladder mounted below the drop wires, between the rungs of which a fallen drop wire is adapted to pass, a trip ladder mounted below the detector ladder, means for reciprocating the detector ladder, loom stopping means, and connections between the 100 trip ladder and the stopping means acting when a drop wire falls to stop the loom and open the drop wires.

2. A warp stop motion for looms having, in combination, a set of drop wires, means 110 for supporting the drop wires, a detector ladder supported below the drop wires, means for continuously reciprocating the detector ladder during the operation of the loom, a trip ladder mounted below the detector ladder, loom stopping means, connections between the trip ladder and loom stopping means, the detector ladder acting through a fallen drop wire to move the trip ladder to stop the loom, and to open the 120 warp by movement of the adjacent drop wires.

3. A warp stop motion for looms having, in combination, a set of drop wires, normally supported by the warp threads dur- 130

ing weaving, a normally stationary but movable trip device below the drop wires and having drop wire engaging portions, a normally reciprocating detector mounted between the drop wires and trip device and having portions for engaging a released drop wire, loom stopping means, and connections between the loom stopping means and the trip device or actuating the former from the latter through the intervention of the detector device pressing against the fallen drop wire between the trip device and the set of drop wires.

4. A warp stop motion for looms having, in combination, a set of drop wires, drop wire bars for supporting the drop wires, heads for carrying the drop wire bars, a detector ladder mounted below the drop wires having rungs adapted to engage a fallen drop wire, means for reciprocating the detector ladder, a trip ladder located below the detector ladder and having rungs adapted to be engaged by a fallen drop wire when the latter is pushed against the rung of the trip ladder by the moving detector ladder rung, stopping means, and connections between the trip ladder and the stopping means for stopping the loom when a drop wire falls.

5. A warp stop motion for looms having, in combination, a set of drop wires, means for supporting them, a detector ladder having rungs supported below the drop wires, a trip ladder having rungs supported below the detector ladder, means for reciprocating the detector ladder, loom stopping means, and connections between the loom stopping means and the trip ladder, the actuating mechanism for the detector ladder having provision for connecting the trip ladder actuating means to restore the ladder to normal position on starting up the loom after stopping.

6. A warp stop motion for looms having, in combination, a set of drop wires, means for supporting the drop wires, a detector device located below the drop wires having

portions adapted to engage a fallen drop wire, a trip device located below the detector device having portions to engage a fallen drop wire, a bell crank lever for reciprocating the detector device, and a second bell crank lever for transmitting motion from the trip device, one of the bell crank levers having portions adapted to engage the other bell crank lever to restore the trip device bell crank lever to its normal position after the loom stopping operation of the motion.

7. A warp stop motion for looms having, in combination, a set of drop wires normally supported by the warp threads during weaving, a detector ladder mounted below the drop wires and between the rungs of which a fallen drop wire is adapted to pass, a trip ladder mounted below the drop wires adjacent the detector ladder, means for reciprocating the detector ladder, loom stopping means, and connections between the trip ladder and the stopping means and operable when a drop wire falls to stop the loom and open the drop wires.

8. A warp stop motion for looms having, in combination, a set of drop wires normally supported by the warp threads during weaving, a detector bar mounted below the drop wires and provided with portions between which a fallen drop wire is adapted to pass, a normally stationary trip bar mounted below the detector bar and also provided with portions between which a fallen drop wire may pass after it has passed, the detector bar to thereby lock the detector bar to the trip bar, means for reciprocating the detector bar in a path between the trip bar and drop wires during weaving, loom stopping means, and connections between the trip bar and the stopping means and operable when a drop wire falls to stop the loom.

In testimony whereof I have signed my name to this specification.

JONAS NORTHROP.
